UNITED STATES PATENT OFFICE.

ZACHARY T. HALL, OF PHILADELPHIA, PENNSYLVANIA.

DESIGN FOR A BROILER.

SPECIFICATION forming part of Design No. 29,714, dated November 22, 1898.

Application filed October 26, 1898. Serial No. 694,633. Term of patent 14 years.

To all whom it may concern:

Be it known that I, ZACHARY T. HALL, a citizen of the United States, residing in the city and county of Philadelphia, State of Pennsylvania, have invented and produced a new and original Design for a Broiler, of which the following is a specification, reference being had to the accompanying drawings, forming part thereof.

10 The leading feature of my design for a broiler is a body having a peripheral guttered rim, separated guttered bars within said rim meeting the same, and necks joining adjacent bars and breaking the spaces between the same.

15 Figure 1 represents a perspective view of a broiler embodying my design. Fig. 2 represents a transverse section thereof on line $x x$, Fig. 1. Fig. 3 represents a longitudinal section thereof on line $y y$, Fig. 1.

A designates the body of the broiler, the same consisting of the peripheral guttered rim B, the separated guttered bars C within said rim meeting the same, and the necks D, which join adjacent bars and break the spaces 25 between the same. E designates a handle which projects from said rim, and F designates a stud which rises from said handle.

Having thus described my invention, what I claim as new, and desire to secure by Letters 30 Patent, is—

The design for a broiler substantially as shown and described.

ZACHARY T. HALL.
